UNITED STATES PATENT OFFICE.

ARTHUR W. LYMAN, OF GENEVA, OHIO.

COMPOUND TOOL.

SPECIFICATION forming part of Letters Patent No. 224,022, dated February 3, 1880.

Application filed September 8, 1879.

To all whom it may concern:

Be it known that I, ARTHUR W. LYMAN, of Geneva, in the county of Ashtabula and State of Ohio, have invented certain new and useful Improvements in Compound Tools; and I do hereby declare that the following is a full, clear, and exact description of the invention, which will enable others skilled in the art to which it appertains to make and use the same, reference being had to the accompanying drawings, and to letters of reference marked thereon, which form a part of this specification, and in which—

The two figures of the drawings are perspective views, Figure 1 representing a top view, and Fig. 2 being an inverted view of Fig. 1.

Corresponding parts in the two figures are denoted by similar letters of reference.

The object of this invention is to furnish the public in general with a new article capable of use for drawing tacks, driving screws, opening cans, and such other uses as necessity may suggest; and to these ends my invention consists of a combined tack-claw, screw-driver, and can-opener constructed all in one piece, substantially as hereinafter more fully described and claimed.

In the accompanying drawings, *a* marks the body of my device, to the ends of which are wrought out devices capable of performing the functions hereinbefore expressed. In the ends of the body *a*, which is preferably curved upwardly, as shown, a **V**-shaped cut, *b*, is made to form a claw, while in the same end, but interiorly of said cut, in a right line, a tongue, *c*, is stamped or otherwise suitably

separated from the body *a*, which forms a fulcrum for the claw *b*.

The other end of my device is of a rectangular form, having three parts, preferably about 40 at right angles to the adjoining part or parts. The first part, *d*, is pointed and sharpened, to be used as a knife or any purpose within its range of use, but more particularly as a can-opener, the plate *e* serving as a slip to prevent 45 the knife from entering the can or other vessel too far, while the part *f*, which constitutes a screw-driver, moving on the perimeter of the vessel, determines and limits the cut to the proper distance from the circumference. 50

The knife-edge extends to a point within the outer end of the plate *e*, and the screw-driver extends beyond both the plate and knife.

Having thus described my invention, what 55 I claim, and desire to secure by Letters Patent, is—

The compound tool herein described, consisting of the body *a*, having at one end a tack-claw, and immediately in rear of same a 60 fulcrum, *c*, stamped from the body *a*, and at the other end a blade, *d*, and stop or plate *e*, having a screw-driver, *f*, at right angles to said stop or plate *e*, all substantially as shown and described. 65

In testimony that I claim the foregoing as my own I affix my signature in presence of two witnesses.

ARTHUR W. LYMAN.
